Wetzel & May

UNITED STATES PATENT OFFICE.

HENRY E. LEPPERT, OF NEW BRITAIN, CONNECTICUT, ASSIGNOR TO THE TRUMBULL ELECTRIC MFG. CO., OF PLAINVILLE, CONNECTICUT, A CORPORATION OF CONNECTICUT.

SNAP SWITCH.

Application filed December 11, 1920. Serial No. 429,909.

To all whom it may concern:

Be it known that I, HENRY E. LEPPERT, a citizen of the United States of America, residing at New Britain, Hartford County, Connecticut, have invented a new and useful Snap Switch, of which the following is a specification.

My invention relates to a rotary type switch, and the main object is to provide a simple and inexpensive construction which is reliable, and the parts of which may be readily assembled.

Another object is to so construct and arrange the parts that they may be accurately made at reasonable cost.

The drawings illustrate one form of mechanism embodying my invention.

Figure 1 is a side view and partial section of a construction embodying the improvements of my invention.

Fig. 2 is a plan view and partial section on the plane of the line 2—2 of Fig. 1.

Fig. 3 is a perspective view of the parts particularly involved in my invention.

The insulating base 5 may be of any suitable construction with any convenient arrangement of terminals, contacts, etc.

The spindle 6 is rotatably supported in the base in a convenient manner, for instance, by the bushing 7, and provided with a suitable finger piece or handle 8 for turning it.

A bearing, abutment, or ratchet plate 9 is secured suitably in the base, for instance, by the bushing 7, and may be prevented from rotating in the base by one or more lugs such as 10 projecting into recesses 11. The plate 9 is provided with a series of lugs such as 12 struck upwardly therefrom and disposed at intervals around the edge thereof. The detent or pawl tooth 13 is carried by a U-shaped plate 14 which embraces one side of the cam 15 carried by the shaft 6. This pawl plate is formed with an opening

16 on one edge so that it embraces only one side of the cam 15, and can be slipped on from the side in assembling the parts. By reason of the pawl plate being open at the side instead of having a hole punched in it for the cam as is customary in structures of this character, it is possible to stamp out the plate so that one side of it will be perfectly smooth, in fact the edges may be rounded somewhat, as indicated at 16' and any burr or roughness will be all on the

opposite face. The usual procedure in stamping out a pawl plate with a hole therein would be to feed flat stock to a press and first punch out a hole in say a downward direction. The upper edge of the hole would be smooth or slightly rounded and a burr would appear on the lower side. The stock having the hole would then be advanced to a point over a die having the contour desired for the pawl plate and a correspondingly shaped punch would move downwardly and force the entire plate into or through the die. This last operation would leave the lower side of the pawl plate smooth or slightly rounded and a burr would appear on the upper side. Thus each side of the finished plate would have a burr and a rounded edge, the burrs occurring at the lower side of the hole and at the outer upper side of the plate while the rounded edges would be at the upper side of the hole and at the under outer side of the plate. By making the pawl plate open at one side as herein disclosed the entire plate may be stamped at one stroke, say in a downward direction, and all the lower edges will be rounded and any burrs occurring will be all at the upper edges. By putting the smooth face against the bearing plate 9, any friction tending to retard the movement of the plate 14 is reduced to a minimum.

On the spindle 6 is mounted another member 17, which may be termed a carrier, which has flanges 18—18 extending toward the plate 9, and serving as guides for the pawl plate 14. This member 17 carries the rotatable contact member 19, which is adapted to make and break contact with the usual stationary contacts (not shown). The carrier preferably has a sleeve 20 on the spindle 6. A spring 21 surrounds the sleeve 20 and has one end connected with the lug 22 on the carrier 17, and the other end connected to the lug 23 on the spindle 6.

The normal position of the parts is as shown in Fig. 1. When the finger piece or handle 8 is turned, the spring 21 is tightened and the rotation of the cam 15 clockwise retracts the pawl tooth 13 from the lug 12 of the abutment plate 9. As soon as the tooth 13 is free of the lug 12, the spring snaps the carrier and pawl plate, and the cam being at that instant relatively stationary, causes the pawl plate to be moved so that the pawl 13 engages the next lug 12 and

- is stopped. By arranging the lugs 12 at the outer edge of the plate 9, a minimum stress is applied to the connection between the plate 9 and the insulating base. There is less danger of the plate working loose or cracking the base than there would be where the lugs are near the axis of the spindle, as is customary in structures of this character.
10. By locating the lugs at the outer edge of the abutment plate, any slight variation in the location of the individual lugs will have less effect on the regular operation of the switch than where the lugs are located nearer to the axis. This also leaves the surface of the plate entirely free from burrs or other irregularities caused by bending or forming lugs in the path of the body of the pawl plate.
15. Instead of fastening the plate 9 to the base by the bushing 7, it may be held in position merely by the assemblage of the spindle and the corresponding parts, or it may be rigidly secured to the base by means of 20 screws passing through the base from the opposite side in the customary manner in structures of this character.

I claim:

1. In a snap switch, an insulating base, 25 an abutment plate carried thereby and having upstanding peripheral stop lugs, a spindle having a cam mounted to rotate adjacent said plate, a flat pawl member engaging one side only of said cam and resting on said plate and having an integral tooth in the plane of said cam and adapted to coact with said stop lugs, a housing mounted on said spindle and having flanges engaging the opposite side edges of said pawl member, 30 and a spring connecting said housing and said spindle.
2. In a snap switch, a base, a spindle rotatable thereon, a bearing plate having stop lugs, a cam on the spindle adjacent the plate, 35 a pawl member on the plate engaging the cam and the stop lugs, a housing having flanges guiding the pawl member and supported on the plate, and a spring engaging the housing and the spindle, said bearing

plate extending beyond the pawl member 40 and the housing to form a support therefor in all positions thereof.

3. In a switch, a spindle, a cam thereon, a bearing plate, a series of lugs projecting from the bearing surface thereof, a pawl 55 plate engaged by said cam and supported on said bearing plate, a member on said spindle housing and guiding said pawl plate, and a spring surrounding said spindle and connected to the spindle and to said member. 60

4. In a switch, a base, a spindle rotatable thereon, a bearing plate having lugs projecting from the face thereof, a cam on the spindle adjacent said plate, a U-shaped pawl member on said plate engaging one side of 65 said cam and having a single tooth for engaging said lugs, a housing having flanges guiding said pawl member, and a spring connecting said housing and said spindle, said bearing plate extending beyond said pawl 70 plate and said housing and forming a support therefor in all positions thereof.

5. In a snap switch, a base, a spindle supported by said base, a cam carried by said spindle, a bearing plate supported by the 75 base and having stop lugs adjacent its periphery, a pawl-plate resting upon said bearing plate and having a tooth for engagement with the stop lugs on said bearing plate, a guide plate mounted upon said spindle and 80 engaging the said pawl-plate and said bearing plate and a spring connecting said spindle and said guide plate, the said pawl plate consisting of a flat imperforate plate of metal having all of its edges on one side 85 of the metal slightly rounded.

6. In a switch, a base, a spindle mounted thereon, a bearing plate having stop lugs, a cam on the spindle adjacent the bearing plate, a pawl member on the plate engaging the stop lugs and the cam, a guide member for housing and protecting the pawl member and a cam and a spring engaging the spindle and the guide member, said bearing plate extending beyond said pawl member 95 and said guide member to provide a protecting support therefor in all positions thereof.

HENRY E. LEPPERT.
